UNITED STATES PATENT OFFICE.

THEODORE H. EICKHOFF, OF CLEVELAND HEIGHTS, OHIO, ASSIGNOR TO PITTSBURGH STEEL COMPANY, OF PITTSBURGH, PENNSYLVANIA, A CORPORATION OF PENNSYLVANIA.

MACHINE FOR FORMING REINFORCEMENT SUPPORTS.

Application filed May 19, 1927. Serial No. 192,595.

My invention relates to machines for forming reinforcement supports or "furring nails," for holding wire fabric in position against studding or other framework, to permit the application of stucco or plaster to said fabric, the fabric serving as a base and a reinforcement for the plaster. My machine is designed more particularly for coiling a spacer upon a nail shank.

10 One object of my invention is to provide a means for forming and assembling reinforcement supporting devices of the type hereinafter referred to.

Another object of my invention is to provide an improved form of machine for coiling wire about a nail or other member.

One form of machine by which my invention may be practised is shown in the accompanying drawing, wherein Figure 1 is 20 a side elevational view; Fig. 2 is a front elevational view, looking from the left hand side of Fig. 1; Fig. 3 is a side elevational view, on an enlarged scale, looking from the left hand side of Fig. 2; Fig. 4 is a view of 25 certain of the parts shown in Fig. 2, but on an enlarged scale, and partially in section; Fig. 5 is a plan view of the apparatus of Fig. 1, on an enlarged scale; Fig. 6 is a view taken on the line VI—VI of Fig. 5, Fig. 7 is a view, on an enlarged scale, of a portion of the apparatus of Fig. 4, showing 30 certain of the parts in the positions occupied at the beginning of the coiling operation; Fig. 8 is a similar view showing positions of the parts at the completion of a coiling operation; Fig. 9 is a view showing the nail raised to ejecting position, and Fig. 10 is a view of 35 a nail containing an element as formed thereon by the apparatus of the other figures.

40 Briefly stated, the invention comprises means for feeding the nails, one by one, to a coiling head; feeding wire; coiling the forward end of said wire about the nail; bending and cutting the wire, and thereafter 45 ejecting the nail.

The nail 11 (Fig. 10) may be of any usual form, but is preferably provided with a wide head, and with notches adjacent to its point. The coil 12 is wound thereon by means to be 50 hereinafter described and the notches prevent accidental slipping of the coil longitudinally of the nail. In use, the point of the nail is placed against studding or other framework and a wire strand or other reen-

forcement member is interposed between the 55 turned-up end 13 of the coil and the head of the nail, whereupon the nail is driven into the studding and the wire strand held between the coil 12 and the head of the nail, the nail sliding through the coil as it is 60 driven. These types of devices are commonly called furring nails and a sufficient number is employed with a wire mesh or the like to properly support the same.

The machine is composed of a framework 65 14 in which is journaled a main shaft 15 that is driven through bevel gearing 16 from a shaft 17 that in turn has connection through bevel gears 18 with a suitable source of power (not shown). A vertically reciprocable 70 head 20 is slidably supported upon the framework 14 and carries a nail feeding plunger 21. The plunger 21 reciprocates in a nail supply chute 22 to eject nails downwardly from said chute. Nails are fed to the 75 chute 22 through spouts 23 to which the nails are supplied from a feed box 24 (Fig. 2) containing feed mechanism which may be of various types such as those employed in connection with various well-known nailing machines, the feeding mechanism being driven from the shaft 15 through a shaft 24^a and bevel gearing 25 in order to deposit the nails, one by one, beneath the feed plunger 21 when it is in its uppermost position.

85 Nail-retaining fingers 26 are pivotally mounted at their upper ends in the sides of the chute 22 and have their lower ends in-turned to temporarily support each nail as it falls beneath the plunger 21. Springs 27 (Figs. 1 and 4) yieldably hold the lower ends of the fingers 26 in their inner positions, but when the plunger 21 descends, it forces a nail past the lower ends of the fingers 26 and itself passes by such ends to carry the nail 90 downward to coiling position.

95 The nail-feeding head 20 is reciprocated by a lifting rod 28 whose upper threaded end extends loosely through an arm 20^a of the head 20 and is adjustably positioned therein 100 by means of nuts 29 and 30, a spring 31 being interposed between the nut 30 and the arm 20^a, to serve as a cushioning element. The lower end of the rod 28 is pivotally connected to a link 32 whose lower end has connection 105 with a lever 33. The lever 33 is pivoted at 34 to the frame work 14 and carries a cam-engaging roller 35 that lies within a cam slot

36 in a disc 37^a (Figs. 3 and 4) which is secured to one face of a bevel gear wheel 37 that is carried by the shaft 15. It will thus be seen that as the shaft 15 rotates, the head 5 20 will be reciprocated and the nails fed downwardly, one by one, from the chute 22.

In order to support the lower end of the nails during their descent, and while the coils 12 are being formed thereon, I provide 10 a supporting plunger 38 (Fig. 4) that extends loosely through a coiler 39 which will be hereinafter described.

The lower end of the plunger 38 has screw-threaded connection with an adjusting 15 sleeve 40 to permit vertical adjustment of the plunger to accommodate it to nails of various lengths, so that the lower end of the plunger 21 and the upper end of the plunger 38 will have properly spaced relation with 20 respect to one another. The adjusting sleeve 40 has screw-threaded connection with a lever 41 that carries a cam roller 42. The cam roller 42 is engaged by a cam 43 that is secured to the shaft 15, so that the plungers 25 21 and 38 will operate in proper synchronism to carry a nail to coil-winding position, and to release the same after completion of the coiling operation. A spring 45 (Fig. 3) serves to hold the rollers 35 and 42 of the 30 levers 33 and 41 in contact with their respective cams.

The wire from which the spacing coils 12 are formed is represented (Figs. 2 and 4) by the reference numeral 47, and may be drawn 35 from a spool (not shown) or other suitable source. The wire is advanced through straighteners 48 of suitable form, by feed rollers 49 and 50, and advanced step-by-step through a thimble or guide block 51, with 40 its forward end some distance beyond the coiler head 39, at the completion of each advance movement, as shown in Fig. 7.

The feed rolls 49 and 50 are driven from the shaft 15 through a cam disc 52 that is 45 secured to the rear face of the gear wheel 37 and is provided with a cam slot 52^a that engages a cam roller 53 on a lever 54^a which supports a link 54 whose upper end has pivotal connection with a rack bar 55. The 50 rack bar 55 is reciprocated vertically during rotation of the shaft 15 and the cam disc 52, and imparts oscillatory movement to a segmental gear 56. The gear member 56 (Fig. 6) has an extension 57 that carries 55 three spring-held pawls 58 whose teeth are yieldably held in contact with the ratchet wheel 59. The ratchet wheel 59 is secured to a shaft 60 that carries a gear wheel 61. The gear wheel 61 meshes with a gear wheel 60 62 that is secured to a shaft 63. The feed rolls 49 and 50 are respectively secured to the shafts 60 and 63.

The pawls 58 are relatively offset along 65 their longitudinal lines (Fig. 4) in order to render it possible to effect a preciseness

of feed which would not be possible unless the ratchet teeth were made exceedingly fine. Assuming the ratchet teeth to have a pitch of $\frac{3}{16}$ " and three pawls offset relative to one another for a distance of $\frac{1}{16}$ ", it will be possible to effect feeding adjustments of a fineness of $\frac{1}{16}$ inch. 70

A bracket 65 (Fig. 4) is secured to the framework 14 and carries a cam-like plate 66 which engages the rear ends of the pawls 58 and is adjustable longitudinally. During oscillatory movements of the member 57 which carries the pawls 58, the rear ends of said pawls are slid back and forth along the upper surface of the cam plates 66, and 80 the teeth of the pawls are held out of engagement with the ratchet teeth until the inner ends of the pawls approach the outer end of the plate 66, which outer end is beveled, to permit the pawl teeth to move into engagement with the ratchet by the pressure of springs 58^a. The position of the plate 66 therefore determines at what point during counter-clockwise movement of the member 57 the pawl will operatively engage the 85 ratchet, and the amount of wire fed during one downward movement of the rack bar 55 can thereby be regulated, it being understood that on its upward movement the rack bar will cause the segmental gear 56 and its extension 57 to move in a clockwise direction, and the pawls 58 to slide over the teeth of the ratchet 59. 90

When advancing movement has been imparted to the wire, as above described, the 100 forward end thereof projects over the coiler head 39 as shown more clearly in Figs. 4 and 7. The coiler head may be of somewhat the usual type, such as employed in the manufacture of twisted joints in wire fencing, and is provided with a wire-engaging or twister lug 39^a, that will engage the wire to twist the same about the nail, in the manner shown in Fig. 8. The coiling head has 105 slidable key connection with a sleeve-like extension 68 (Fig. 4) of a gear wheel 69 that meshes with the bevel gear wheel 37. The coiler head 39 is yieldably supported against downward movement by a spring 71 whose lower end is supported upon an adjusting nut 72. The nut has screw-threaded connection with an internal thread of the hub of the gear wheel 69, to permit of adjustment of the spring tension. 110

When the forward end of the wire 47 is 115 advanced to the position shown in Figs. 7 and 4, it is bent down into contact with the coiling head 39, so as to be engaged by the stop lug 39^a, by a finger 73 (Figs. 3 and 4). The finger 73 is mounted upon a rock shaft 120 74 that has a crank-like extension 75 whose lower end carries a cam roller 76 which is engaged by a cam 77 during each revolution of the shaft 15, to rock the shaft 74 and cause the finger 73 to depress the wire 47 to the 125 130

position indicated by dotted lines in Fig. 7, so that it will be engaged by the stop 39^a and coil around the nail 11. The cam 77 is secured to the rear face of the gear wheel

5 37.

It will be understood that while various of the parts just described have only intermittent movement, the coiler 39 is constantly rotating, so that when the wire is depressed 10 into engagement with the coiler, it will be immediately wound around the nail which is held between the plungers 21 and 38, the coiler head being forced down against the compression of the spring 71 as the winding 15 progresses to the extent indicated in Fig. 8.

When the last turn of the wire has been completed, the stop 39^a will idle around the lower portion of the coil until the coil has been severed from the main strand and the 20 plungers 21 and 38 elevated.

In order to sever the coil from the main body of wire, I provide a cutter arm 80 which is mounted upon an oscillatory head 81. The head 81 has an extension 82 (Fig. 25 4) that has connection through an adjustable link structure 83 with a slide 84. The slide 84 carries a cam roller 85 which is supported within the cam slot 52^a in which the cam roller 53 for the rack bar 55 also lies 30 (Fig. 3).

When the wire has been advanced and coiled as above described, the parts are so timed that the cutter head 81 will be rocked from the position shown in Fig. 7 to that 35 shown in Fig. 8, to sever the wire and to form the bend 13 in its upper end. The cutter 80 is provided with a rounded projection or nose as shown more clearly in Fig. 8 so that the upper portion of the coil is bent 40 previous to being severed by the knife edge of the rear of such nose portion. The cutter 80 is held in position upon its head 81 by screws or bolts 87 (Figs. 3 and 7) and the heads of these bolts extend such distance 45 that they will engage a plate 39^b that is carried on the upper end of the coiler head, to prevent the knife 80 from engaging the coiler head, and injuring the same, as in cases where no wire is present to form a coil 50 and cause the coiler head to move down immediately preceding actuation of the knife 80. In such cases, the bolt heads will engage the plate 39^b and prevent the knife blade from coming into contact with the 55 coiler head.

At the completion of the coiling and cutting-off operation, the plungers 21 and 38 are moved upward by their respective cams, but the movement of the plunger 38 is somewhat slower than that of the plunger 21, so that the nail is released during upward movement of the head 20 and its plunger 21. A pawl 88 that is pivotally mounted on the head 20, engages the upper end of a nail-ejecting finger 89 which is pivotally mounted

on the side of the chute 22, as shown in Figs. 2 and 3. The finger has a horizontally bent lower end 90 which is swung against the nail 11 to eject or throw the same clear of the machine, when the plunger 21 has risen to a point slightly above its full-line position 70 in Fig. 9. Movement of the pawl 88 in a clockwise direction is limited by a stop 91, against which it is normally held by a spring 92. This arrangement permits the pawl to descend past the upper end of the finger 89 when the head 20 is descending, but rigidly supports the same against clockwise movement when ascending, so that the finger 89 is positively actuated to eject the nail. 80

After ejection of the nail, there is still further lag in upward movement of the plunger 38 with respect to the plunger 21, to permit the plunger 21 to rise sufficiently far that another nail can fall beneath the same and be engaged by the plunger in its downward movement, as indicated by the dotted lines in Fig. 9, by the time the plunger 38 has reached its uppermost or nail-receiving position. The ends of the nail are therewith engaged by the plungers 21 and 38 and downward movement thereof to coiling position begins. 90

I claim as my invention:—

1. Apparatus comprising means for feeding nails and supporting the same, means for positioning a wire in position to be coiled about said nail, and means for coiling said wire about the nail. 95

2. Apparatus comprising means for feeding nails and supporting the same, means for advancing a wire transversely of the nail, a coiler head, and means for effecting engagement between said coiler head and said wire to coil the wire about the nail. 100

3. Apparatus comprising means for feeding nails and supporting the same, means for advancing a wire, a coiler head, means for effecting engagement between the wire and the head to coil the wire about the nail, and means for severing the coil so formed from the main body of wire. 110

4. Apparatus comprising means for feeding nails and supporting the same, means for advancing a wire, a coiler head, means for effecting engagement between the wire and the head to coil the wire about the nail, and means for severing the coil so formed from the main body of wire and for bending that end of the coil adjacent to the point of severance to cause the same to extend in the same general direction as the nail but in spaced relation to the shank of the nail. 120

5. Apparatus comprising means for feeding nails, means for intermittently advancing a wire strand, means for coiling the forward end of said strand about a nail and means for severing the coil so formed from the said strand. 125

6. Apparatus comprising axially spaced 130

plungers, means for placing nails in position to be engaged by said plungers, means for advancing a wire strand between said plungers, and a coiler head for twisting the said wire about the nail.

7. Apparatus comprising axially spaced plungers, means for placing nails in position to be engaged by said plungers, means for advancing a wire strand between said plungers, a coiler head disposed coaxially of said plungers, in position to engage and twist the said wire about the nail, and means permitting movement of said head longitudinally of the nail during coiling of the wire.

10 8. Apparatus comprising a plunger for engaging one end of a nail, a second plunger for engaging the other end of the nail to support the same, means for positioning a wire, and a coiler head for twisting said wire about the nail.

15 9. The combination with a nail chute, of a plunger movable past the lower end of said chute, a second plunger disposed in parallelism with the first-named plunger in position to engage nails advanced from said chute by the first-named plunger, means for advancing a wire between adjacent ends of said plungers and a coiling device for wrapping the wire around the nail.

20 10. The combination with a nail chute, of a plunger movable past the lower end of said chute, a second plunger disposed in parallelism with the first-named plunger in position to engage nails advanced from said chute by the first-named plunger, means for advancing a wire between adjacent ends of said plungers, and a coiling device surrounding one of said plungers in position to engage and wrap the wire around the nail.

25 11. The combination with a nail chute, of a plunger movable past the lower end of said chute, a second plunger disposed in parallelism with the first-named plunger in position to engage nails advanced from said chute by the first-named plunger, means for advancing a wire between adjacent ends of said plungers, a coiling device surrounding one of said plungers in position to engage and wrap the wire around the nail, and means permitting axial movement of the coiling device relative to the said plungers during the coiling operation.

30 12. The combination with a nail chute, of a plunger movable past the lower end of said chute, a second plunger disposed in parallelism with the first-named plunger in position to engage nails advanced from said chute by the first-named plunger, means for advancing a wire between adjacent ends of said plungers, a coiling device surrounding one of said plungers in position to engage and wrap the wire around the nail, means permitting axial movement of the

coiling device relative to the said plungers during the coiling operation, and means for severing the coil from said strand at the completion of a coiling operation.

35 13. The combination with a nail chute, of a plunger movable past the lower end of said chute, a second plunger disposed in parallelism with the first-named plunger in position to engage nails advanced from said chute by the first-named plunger, means for advancing a wire between adjacent ends of said plungers, a coiling device surrounding one of said plungers in position to engage and wrap the wire around the nail, means permitting axial movement of the coiling device during the coiling operation, means for severing the coil from said strand at the completion of a coiling operation, and means for effecting movement of one of said plungers to release the nail after the coiling operation.

40 14. The combination with a nail chute, of a plunger movable past the lower end of said chute, a second plunger disposed in parallelism with the first-named plunger in position to engage nails advanced from said chute by the first-named plunger, means for advancing a wire between adjacent ends of said plungers, a coiling device surrounding one of said plungers in position to engage and wrap the wire around the nail, means permitting axial movement of the coiling device during the coiling operation, means for severing the coil from said strand at the completion of a coiling operation, means for effecting movement of one of said plungers to release the nail after the coiling operation, and means controlled by said plunger for ejecting the nail from between the plungers.

45 15. The combination with coiling apparatus, of means for advancing a wire to be coiled, a vertically movable plunger, means for positioning a nail in front of said plunger, a second plunger, means for moving said second plunger into position to engage the other end of said nail, and means for moving said plungers to bring the nail into proximity with the coiling head and the wire to permit coiling of the wire about the nail.

50 16. The combination with means for positioning a wire, and a coiling device therefor, of an axially movable plunger, means for positioning a nail in front of said plunger and in axial alinement therewith, a second plunger axially movable with respect to the first-named plunger, and means for imparting relative axial movements to said plungers in order to alternately engage wire nails upon which coils are to be formed.

In testimony whereof I the said THEODORE H. EICKHOFF, have hereunto set my hand.

THEODORE H. EICKHOFF.
